Primary Examiner — Khawaja Anwar

(57) **CLAIM**

The ornamental design for an ice mold, as shown and described.

DESCRIPTION

1. Ice mold
2. Ice mold
1.1 : Perspective
1.2 : Perspective
1.3 : Front
1.4 : Back
1.5 : Left
1.6 : Right
1.7 : Top
1.8 : Bottom
1.9 : Exploded
1.10 : Perspective
2.1 : Perspective
2.2 : Perspective
2.3 : Front
2.4 : Back
2.5 : Left
2.6 : Right
2.7 : Top
2.8 : Bottom
2.9 : Exploded
2.10 : Perspective
1.1: Top perspective view of an ice mold showing our new design; 1.2: Bottom perspective view thereof; 1.3: Front elevational view thereof; 1.4: Rear elevational view thereof; 1.5: Left side elevational view thereof; 1.6: Right side elevational view thereof; 1.7: Top plan view thereof; 1.8: Bottom plan view thereof; 1.9: Exploded perspective views thereof; and, 1.10: Top perspective view of the ice mold of 1.1 with handle open 45 degrees; 2.1: Top perspective view of an ice mold showing our new design; 2.2: Bottom perspective view thereof; 2.3: Front elevational view thereof; 2.4: Rear elevational view thereof; 2.5: is a left side elevational view thereof; 2.6: is a right side elevational view thereof; 2.7: is a top plan view thereof; 2.8: is a bottom plan view thereof; 2.9: is an exploded perspective views thereof;

(Continued)

2.10: is a top perspective view of the ice mold of **2.1** with handle open 90 degrees thereof; and the broken lines form no part of the claimed design.
